UNITED STATES PATENT OFFICE.

CLINTON L. WOLFE AND JOSEPH A. FAUROT, OF NEW YORK, N. Y.

SPEAK-HOLE FIXTURE.

Application filed June 8, 1926, Serial No. 114,490. Renewed October 26, 1927.

The present invention relates to speak-hole fixtures and has for its object to provide a fixture of this kind which will prevent the shooting of a bullet through the speak-hole without interfering with the passage of sound therethrough.

The invention will be more particularly described in connection with the accompanying drawing in which,

10 Fig. 1 is a front elevation of a bank teller's window showing the location of the speak-hole fixture;

Fig. 2 is a vertical section through the center of the teller's window; and

15 Fig. 3 is an enlarged side view of the speak-hole fixture per se, parts being shown in section.

The fixture comprises two outside clamping plates 1 and 2, and a centrally disposed bullet-proof diaphragm 3. A threaded stud 4 extends outward from the center of plate 1, and the diaphragm 3 and plate 2 are provided with centrally located threaded holes 5 and 6 whereby they are screwed onto 20 the stud 4. The window 7, which is made of bullet-proof glass, has an opening 8 in which the fixture is secured.

In mounting the fixture in position the diaphragm is first screwed onto stud 4, the assembled plate 1 and diaphragm are then inserted in the opening 8, and the plate 2 is finally screwed onto stud 4 clamping the window between the two outer plates. A nut 9 and washer 10 may be applied to the outer end of stud 4 to hold the parts in position.

The diaphragm is somewhat smaller in diameter than the opening 8, and plates 1 and 2 are provided with shoulders 11 which rest against the circumference of the opening 8, thereby holding the fixture in concentric relation to the opening 8, and maintaining a free space between the edges of the diaphragm and the circumference of the opening 8. Obviously the shoulders 11 might be replaced by any other form of abutment such as a series of lugs arranged in a circle on the plates 1 and 2. The outer plates 1 and 2 are provided with openings 12 for the passage of sound waves which are transmitted through the fixture by the diaphragm and also pass around the edges of the diaphragm.

The tray may be of the ordinary flat variety or of the construction shown at 13 in Fig. 2. The tray here shown has the advantage that it permits the teller to shoot through the thin outer wall 14 but prevents a robber from shooting through the thick wall 15 at the teller. This tray will be more 60 particularly described and claimed in another application.

It will be seen from the above description that I have provided a speak-hole fixture of simple construction which will completely 65 prevent the passage of a bullet, but which permits free passage of sound, thereby facilitating conversation between the teller and a customer without endangering the life of the teller by providing an opening through 70 the customary bullet-proof glass through which a holdup man might shoot.

Having described my invention, I claim:

1. A fixture for a bank teller's window comprising in combination with a bullet-proof window having a speak-hole therein, a pair of outer plates, means for clamping said plates against opposite sides of said window around the circumference of said speak-hole, openings in said plates, and a 80 bullet proof diaphragm mounted in spaced relation between said plates and extending across the openings therein.

2. A fixture according to claim 1 in which one of said plates is provided with a threaded stud upon which the diaphragm and the other plate are mounted.

3. A fixture according to claim 1 in which the diaphragm is of slightly smaller diameter than the speak-hole, and the plates are 90 provided with abutments for holding the diaphragm in spaced relation with respect to the circumference of the speak-hole.

4. The combination with a speak hole through a partition of a fixture for preventing the passage of a bullet through the speak hole comprising perforated outer plates, means for clamping said outer plates on opposite sides of said partition around the circumference of said speak hole and a 100 diaphragm between said plate extending across said perforations.

In testimony whereof the foregoing specification is signed.

CLINTON L. WOLFE.
JOSEPH A. FAUROT.
